UNITED STATES PATENT OFFICE.

FRANK G. LYON, OF JERSEY CITY, NEW JERSEY, ASSIGNOR TO THE HOLMES ELECTRIC PROTECTIVE COMPANY, OF NEW YORK, N. Y.

ELECTRIC BURGLAR-ALARM.

SPECIFICATION forming part of Letters Patent No. 316,376, dated April 21, 1885.

Application filed September 29, 1884. (No model.)

To all whom it may concern:

Be it known that I, FRANK G. LYON, of Jersey City, in the county of Hudson and State of New Jersey, have invented a certain new and useful Improvement in Electric Burglar Alarms, of which the following is a specification.

This improvement relates to electric burglar alarms of the kind wherein an electric circuit extends from a house or other building which it is desired to guard to an office where watchmen are kept.

It has occasionally happened with these burglar-alarms that burglars have forced open a door leading to a guarded building, hastily seized some valuables therein, and escaped before the watchman at the office could after hearing the alarm caused by the entrance of the burglars reach the guarded building.

The object of my improvement is to prevent burglars from successfully working in the manner described.

To this end the improvement consists in the combination of an electric circuit extending between a guarded building and an office where watchmen are kept, a door or like article in the guarded building, a lock, bolt, or analogous fastening for the door or like article, a circuit-closing device operating to fulfill its function when the door or like article is opened partially, a chain preventing the door or like article from being opened sufficiently wide to admit a burglar, but made of such length that force by which the lock, bolt, or analogous fastenings of the door may be broken will not act to break the chain, and of such length that it will permit the door or like article to be opened wide enough to enable the circuit-closing device to operate.

A burglar breaking the lock, bolt, or analogous fastening of the door by force exerted with a jimmy in the ordinary manner will find the door still secured by the chain, which will not have been broken in the act of breaking the lock, bolt, or analogous fastening. He will, however, have opened the door far enough to cause the circuit-closing device to operate, and hence the watchman at the office will have been apprised of his action. While he is occupied in endeavors to sever the chain

the watchmen will be afforded time to proceed toward the building. Through my improvement, therefore, the kind of burglaries to which I have referred will be more easily frustrated.

In the accompanying drawings, Figure 1 is a diagram illustrating an office where watchmen are kept, the inner side of a pair of doors belonging to a guarded building, and an electric burglar-alarm embodying my improvement. Fig. 2 is a view of a circuit-closing device used in the burglar-alarm, and Fig. 3 is a view of chain-sections and a padlock.

Similar letters of reference designate corresponding parts in all the figures.

I have marked the word "Office" upon that part of Fig. 1 which is intended to represent the office where watchmen are kept, and I have also marked the words "Guarded Building" upon the part designed to represent the guarded building.

A A' designate a galvanometer, Δ designating the coils and A' the needle. The coils are connected together in the usual manner.

From the pivot of the galvanometer-needle a wire, B, extends to an electro-magnetic alarm-bell, C, thence a wire, B', extends to an electric battery, D, and thence a wire, B'', extends to contact-points E E', in conjunction with which the needle A' of the galvanometer operates. The wires B B' B'', the electro-magnetic bell C, and the battery D are all in one local circuit, which is arranged in the office. Whenever the galvanometer-needle is deflected against either of the contact-points E E', it closes the local circuit and causes the electro-magnetic bell to sound an alarm.

F designates an electric battery (shown as arranged in the office.) One pole is connected by a wire, G, with one of the coils of the galvanometer. The other coil of the galvanometer is connected by a wire, G', with a switch or key, H, which, as here shown, is pivotally secured to the inner side of a door, I, belonging to the guarded building, so that it may be swung into and out of contact with a contact-point, H', which is also affixed to the said door.

From the contact-point H' a wire, G'', extends to a resistance-coil, J, located in the guarded

building. This wire, before reaching the resistance-coil, is also electrically connected to a movable metal pin, K', comprised in a circuit-closing device, which is operated by the door I.

From the resistance-coil J a wire, G², extends to the battery F. This wire is also connected to a metal contact-piece, K³, which is comprised in the short-circuiting device before referred to.

The circuit-closing device is secured to the frame of the door. It has a base-plate, K, which may be made of metal. The metal pin K' before mentioned slides through it and another bearing which extends from the plate. This pin carries a metal contact-piece, K². A spring, K⁴, surrounding this pin K' between its rear bearing and the contact-piece K², impels the spring outward whenever it can. The contact-piece K³ is fastened to a block, K⁵, of wood or other insulating material, that is affixed to the base-plate K. This contact-piece K³ is resilient.

When the door I is closed, it presses the pin K' inward against the resistance of the spring K⁴. The contact-piece K² is thus carried away from the plate K, and also away from the contact-piece K³. The contact-piece K³, owing to its resilience, also moves a slight distance away from the plate K.

When the door I is opened even a short distance, the pin K' will move outward, and the contact-piece K² will make contact with contact-piece K³ and force the latter against the plate K. The resistance-coil J will thus be short-circuited and the galvanometer-needle will be deflected so as to cause the sounding of an alarm at the office.

The door I, as shown, operates in conjunction with a door, I'. The door I' is fastened, as usual, by bolts, and the door I, which is the master door, is fastened to it by a lock, bolt, or analogous fastening, L. Such fastening will hold the door closed tightly.

M M' designate two sections of chain fastened one to the inner side of the door I and the other to the same side of the door I'. A padlock, I², secures the free ends of these sections of chain together. The chain M M' is so loose that force exerted by a jimmy or analogous implement to force the door I open will be so far expended before it acts on the chain that the chain will not be broken. It is also long enough to permit the door to open sufficiently far to allow the short-circuiting device to operate and short-circuit the resistance-coil, so as to cause an alarm at the office. It is not, however, long enough to admit a burglar past the door. The burglar endeavoring to effect an entrance into the guarded building has still to sever the chain or break the padlock. While he is engaged in efforts to do this the watchmen at the office will be afforded time to proceed to-

ward the guarded building. May a burglary 65 may be frustrated in this way. Preferably these chain-sections will comprise swivels m m', so that they cannot be broken by twisting them.

The ends of the chain-sections M M' may be 70 united by the padlock when door I is partially closed, and while the inmates of the guarded building are outside the door. They can accomplish this by thrusting their hands between the door I and the door I', slipping 75 the hasp of the padlock through the end links of the chain-sections, and then locking the padlock. The door I may then be entirely closed and locked.

The key H enables the inmates of the guarded building on returning to it to give a preconcerted signal, and thus indicate the difference between themselves and a burglar to the watchmen at the office.

Obviously the improvement is applicable 85 to articles other than doors.

What I claim as my invention, and desire to secure by Letters Patent, is—

1. The combination of an electric circuit extending between a guarded building and an 90 office where watchmen are kept, a door or like article in the guarded building, a lock, bolt, or analogous fastening for the door or like article, a circuit-closing device operating to fulfill its function when the door or like article 95 is opened partially, a chain preventing the door or like article from being opened sufficiently wide to admit a burglar, but made of such length that the force by which the lock, bolt, or analogous fastening of the door or like 100 article may be broken will not act to break the chain, and of such length that it will permit the door or like article to be opened wide enough for the circuit-closing device to operate, substantially as specified. 105

2. The combination of an electric circuit extending between a guarded building and an office where watchmen are kept, a door or like article in the guarded building, a lock, bolt, or analogous fastening for the door or like article, a circuit-closing device operating to fulfill its function when the door or like article is opened partially, a chain comprising swivels and preventing the door or like article from being opened sufficiently wide to admit 115 a burglar, but made of such length that the force by which the lock, bolt, or analogous fastening of the door or like article may be broken will not act to break the chain, and of such length that it will permit the door or like 120 article to be opened wide enough for the circuit-closing device to operate, substantially as specified. 110
